UNITED STATES PATENT OFFICE.

ALFRED H. KELCH, OF LAKE VIEW, IOWA.

TUBE OR FLUE CUTTER.

1,158,504.

Specification of Letters Patent.

Patented Nov. 2, 1915.

Application filed February 6, 1915. Serial No. 6,498.

To all whom it may concern:

Be it known that I, ALFRED H. KELCH, a citizen of the United States, residing at Lake View, in the county of Sac and State of Iowa, have invented a new and useful Tube or Flue Cutter; and I do hereby declare the following to be a full, clear, and exact description of the invention, such as will enable others skilled in the art to which it appertains to make and use the same.

This invention relates to an improved tool for cutting the ends of flues or tubes of a stationary or locomotive boiler, upon the inside of the flue sheet, which tool comprises improved features as claimed.

The invention comprises further features and combination of parts, as hereinafter set forth, shown in the drawings and claimed.

In the drawings:—Figure 1 is a view showing the flue cutter in the position in connection with one end of the tube or flue, showing the handle thrown at right angles in dotted lines, whereby the tool may be rotated partially, for instance only the width 25 of the cutter, that is, after making an incision with the cutter. Fig. 2 is a sectional view on line 2—2 of Fig. 1. Fig. 3 is a sectional view on line 3—3 of Fig. 1. Fig. 4 is a view, showing a portion of the tool head, 30 the U-shaped clamp and the cutter proper, illustrating said parts disassembled.

Referring more especially to the drawings, 1 designates the tool head having a disk-shaped portion 2 at one end, the peripheral portion of which is provided with notches 3. A handle member 4 is provided, which comprises the two sections 5 and 6, the section 6 is threaded at 7 into a hollow portion of the section 5, while the outer portion or end of the section 5 may be grasped by the hand of an operator for operating the device.

The section 6 is provided with a bifurcation 8, the side arms 9 of which engage opposite flat faces of the disk-shaped portion 2 of the head 1, there being a suitable pivot pin 10 for pivotally connecting said parts. The side arms 9 of the section 6 are provided with elongated slots 11, to receive the 50 U-shaped block or dog 12, the portion 13 of which is designed to engage any one of the notches 3 of the disk 2 to hold the handle member in adjusted position, whereas the arms 14 of the block or dog engage upon the 55 outer surfaces of the arms 9 to prevent transverse displacement of the dog. A

spring 15 is interposed between the dog 12 and the crotch 16 of said bifurcation, to hold the dog in any one of said notches.

The head 1 is constructed with a pair of angular recesses or cutaway portions 17 and 18. The angular recess 17 has its shoulder 19 engaging the peripheral flange 20 of the end of the flue, while at the same time the curved portion 21 of the tool head engages 65 the end of the flue as shown in Fig. 1, thereby guiding the tool in its work.

In using the device the interior periphery of the tube or flue adjacent to the peripheral flange 20 is supplied with heavy grease, 70 thereby allowing the curved portion 21 of the head to slide into the flue or tube when the handle is depressed, in order to force the cutting edge of the cutting tool proper through the wall of the flue or tube. After 75 the cutting edge of the cutter proper has been forced through the wall of the tube, the handle is swung to such a position, that the device may be rotated just the width of the cutter, then the handle is swung in the position shown in full lines, after which downward pressure upon the handle is exerted, to again force the cutting edge through the 80 wall.

The opposite faces of the tool head 1 are 85 constructed with recesses 22 which receive the opposite sides 23 of the U-shaped flange, there being a headed screw threaded pin 24 to hold the clamp in position. This pin 24 passes through the sides of the U-shaped 90 clamp and through the tool head 1, and is threaded in one of the sides of the U-shaped clamp, as shown clearly in Fig. 2. Before placing the U-shaped clamp in position as illustrated in Figs. 1 and 2, the cutting tool 95 proper 25 is arranged in the recess 18, there being a set screw 26 threaded through the end of the U-shaped clamp and designed to frictionally engage the cutting tool 25 proper. The cutting tool proper 25 has a 100 V-shaped upper portion provided with a cutting edge 27, which, when the device is arranged as shown in Fig. 1, engages the inner circumference of the flue adjacent the flue sheet.

After the device has been arranged as shown in Fig. 1 downward pressure is manually exerted upon the handle 4, thereby forcing the curved portion 21 of the head into the tube, said curved portion thereby 110 slides upon the interior periphery of the tube adjacent the flange 20. As pressure is

applied downwardly on the handle 4 the cutting edge of the tool 25 is forced through the wall of the flue or tube. Consecutively after each time the cutting edge of the tool 5 is forced through the wall of the tube, the device is manipulated to withdraw the tool 25 from the cut, the handle 4 being then arranged in such a position as to rotate the device partially, say for instance, the width 10 of the cutting tool immediately adjacent to the previous cut, then the handle is returned to the position shown in full lines, and downward pressure applied thereon, thereby causing the cutting edge to make another 15 incision. These operations are consecutively repeated, until the flue or tube is entirely severed. However, it is to be understood, that before making these consecutive cuts or incisions, an annular gage or guide line 20 may be marked or scored by the cutting edge of the tool 25. This is accomplished by throwing the handle 4 in the position shown in dotted lines, and a rotary motion imparted to the device. After the gage or 25 guide line is scored or marked, the cutting of the flue or tube may proceed as before stated.

The invention having been set forth, what is claimed as new and useful is:—

- 30 1. In combination with a flue cutter head having a pair of angular cutaway portions, a shoulder of one of which is designed to engage the inner end surface of the flue, while the portion of the head opposite said 35 shoulder engages the opposite inner surface of the flue end, a V-shaped cutting tool proper engaging the other angular cutaway

portion having its cutting edge engaging the inner surface of the flue, a U-shaped clamp having means to hold the cutter proper in 40 the angular cutaway portion, means for holding the U-shaped clamp in place, and a handle having such connections with the head that the handle may be thrown at different angles to the head. 45

2. In combination with a flue cutter head having a pair of angular cutaway portions, a shoulder of one of which is designed to engage the inner end surface of the flue, while the portion of the head opposite said 50 shoulder engages the opposite inner surface of the flue end, a V-shaped cutting tool proper engaging the other angular cutaway portion, having its cutting edge engaging the inner surface of the flue, the opposite 55 side faces of the head having diametrically opposite recesses, a U-shaped clamp arching the head and engaging the diametrically opposite recesses for holding the cutter proper in place, a set screw engaging through the 60 end of the U-shaped clamp to hold the cutter tool proper in place, means passing through the sides of the clamp and the head for holding the same in place, and a handle having such connections with the head, that the 65 handle may be thrown substantially at right angles to the head.

In testimony whereof I have signed my name to this specification in the presence of two subscribing witnesses.

ALFRED H. KELCH.
